UNITED STATES PATENT OFFICE

OLIVER M. EDWARDS, OF SYRACUSE, NEW YORK, AND JOHN F. LEVAN, OF ELKHART, INDIANA, ASSIGNORS TO THE O. M. EDWARDS COMPANY INC., OF SYRACUSE, NEW YORK, A CORPORATION OF NEW YORK

WINDOW GUIDE AND SASH CONSTRUCTION

Application filed April 8, 1930. Serial No. 442,645.

This invention relates to window guide and sash construction particularly applicable for railway cars, busses and other vehicles where the window guides and sashes are furnished by a manufacturer and applied by the car builder to the window openings in the car body.

It has for its object, a particularly simple and efficient window guide construction by which the sash is held at all times snugly against rattling and air drafts in the guide.

The invention consists in the novel features and in the combinations and constructions hereinafter set forth and claimed.

In describing this invention, reference is had to the accompanying drawings in which like characters designate corresponding parts in all the views.

Figure 1 is a fragmentary elevation of a window guide and sash embodying our invention.

Figure 2 is an enlarged sectional view on line 2—2, Figure 1.

Figure 3 is an inner face view on a reduced scale of the detachable member of the guide.

Figure 4 is a face view of the body of the guide.

Figure 5 is an elevation, partly in section, of a corner portion of the sash showing the sash holder arrangement.

Figure 6 is an edge view of the sash looking to the right Figure 5, the sash guide being omitted.

Figure 7 is an enlarged fragmentary view of the lower end of the guide showing the means for holding the removable side of the guide from vertical movement with the sash.

Figure 8 is a sectional view on line 8—8, Figure 7.

This window guide and sash construction comprises generally, a guide or post structure or member formed with a channel for receiving the sash, the bottom of the channel being located intermediate the inner and outer edges of the guide, and the guide consisting of two main members, one a body formed with one side wall and the bottom of the channel, and the other, a detachable member having a portion forming the other side wall of the channel and a portion lapping or covering the

contiguous side of the body between the bottom of the channel and the wall of the window opening, the detachable member being fulcrumed between its inner and outer edges on the body, and means for moving the detachable member on its fulcrum to press it against the sash, this means being a spring preferably interposed between the lapping portions of the body and the detachable member.

1 designates the frame of the sash which is usually formed up of sheet metal, the sash frame being provided with any suitable means for holding a glass pane 2.

3 designates the body of the guide or post structure or member, this being preferably formed up of sheet metal to provide one of the walls 4 of the channel 5 which receives the sash, and with the bottom 6 of the channel, which bottom is spaced apart from the wall 7 of the window opening in the car body or other structure. The body 3 is secured in the window opening in any suitable manner.

As here illustrated, the body is struck up from a single piece of sheet metal and folded upon itself at 8 to form one wall of the reentrant channel 5, the bottom 6 being integral with the reentrant portion and also the wall 9 of the body being integral with the bottom 6 of the channel, this wall 9 being interposed between the bottom 6 of the channel and the wall 7 of the window opening. Thus, the body is formed hollow with the bottom 6 of the channel between its inner and outer edges.

10 designates the detachable member which forms the other side of the channel 5, this being also formed up of sheet metal and being bent upon itself at 11 providing a double wall portion, the inner wall of which is formed with prongs 12 for entering slots 13 in the bottom of the channel, these slots being located near the junction of the bottom 6 and the wall 9, or at the edge of the bottom remote from the wall 4 of the channel. The prongs 12 are preferably located in line with the portion of the member 10 which presses against the same, and are shown as hook shaped so as to interlock with the slots 13 upon successive inward movement of the member 10 to carry the prongs through the

slots and endwise to interlock the hooks in the slots. The detachable member is also formed with an offset flange or wall 14 covering and opposed to the outer face of the wall 9 and spaced apart therefrom. A spring 15 is interposed between the spaced apart walls 9 and 14 and tends to impart a movement to the detachable member 10 to cause it to tend to rock or to rock or fulcrum to a slight extent about the points of engagement of the prongs 12 with the walls of the slot 13, and thus press the detachable member against the sash and thrust it toward the wall 4 of the channel thus holding the sash against rattling and also holding it snugly in the channel so as to prevent the passage of air drafts. The fact that the sash is flat and also the face of the sash against which the member 10 presses is flat causes the member 10 to have, within limits, a rectilinear movement under the force of the spring 15 or the rocking or fulcruming tendency is to some extent converted into a rectilinear movement, within limits. In any event, the member 10 is pressed snugly against the sash. The bottom 6 is wider than the sash in order to locate the slots 13 outside of the space occupied by the sash.

The spring 15 may be of any suitable form, size and construction, and as here shown, is in the form of a leaf or strip running lengthwise of the walls 9 and 14, the strip having a base portion 16 in the form of a U which embraces the wall 9, the intermediate portion of the U formation extending around the outer edge of the wall 9 and interposed between such edge and the wall 7 of the opening in which the guide is mounted, so that the securing of the guide 3 in the window opening also secures or anchors the spring in position. There are two guides one along each side edge of the sash.

A sash is provided with sash holders one at each lower corner. The sash holder comprises a base 18 mounted on the outer face of the bottom rail of the sash, an operating lever 19 pivoted at 20 to the base plate and having an arm arranged in pinch handle relation to a lift shoulder 20 on the base plate, an angular 50 arm 21 extending in a hollow box portion 22 of the casing, a bolt 23 slidably in the bottom rail and having a nose 24 projecting through the edge wall of the sash, the bolt being connected at 25 to the lever arm 21 by a pin 26 extending through a slot 27 in the wall of the hollow bottom rail. The bolt is pressed outwardly by a spring 28. The bolt is suitably guided in the bottom rail. The nose 24 enters holes or depressions 29 formed in the bottom 6 of the channel at suitable intervals.

When the sash is closed, the nose enters a hole 29 in the bottom of the channel.

The locking member or bolt is located within the sash in position to coact with 65 openings or indentations or rack means in

or on the bottom of the channel and does not interfere with the removable strip or detachable member 10 and further does not have to be widened to support a rack or other means to coact with the bolt of the sash holder.

As the detachable member 10 is moved into its final position by a downward endwise movement, which interlocks the projections or prongs 12 in the slots 13, means is provided for locking it from possible upward displacement when the sash is raised.

As here illustrated and preferably, this means consists of one or more slots as the stop 31 in the lapping portion 14 of the member 10 and a tongue 32 struck from the spring for entering the slot only when the detachable member is properly located. To remove the member 10, the tongue must be first pushed out of the slot with any suitable tool.

In order to locate the spring 15 relatively to the body 3 of the guide so that it will in turn locate the detachable member, the spring and the wall 9 of the guide which the spring embraces are provided with interlocking parts which coact snap catch fashion. This consists of a tongue or projection 33 on the spring and a mating depression or hole 34 in the wall 9. Preferably, the tongue 33 for interlocking with the wall 9 and the tongue 32 for interlocking with the detachable member are located near one end and usually the lower end of the spring 15.

In operation, the bodies of the guides are secured in the window opening with the springs 15 in position, then the sash is mounted in the bodies and then the detachable members applied by a successive inward movement to carry the prongs 12 through the slots 13 and endwise movement to interlock the prongs in the slot. The applying of the detachable members 10 tensions the springs 15 so that the spring acts to rock the members 10 about the points of engagement of the prongs 12 of the walls of the slot 13, and thus, press the member 10 against the sash and hold the sash snugly in the channel.

This guide and window construction is particularly advantageous in that it is simple and economical in construction, consists of but few parts which are readily assembled in a window opening. Also, owing to the detachable member, the sash can be readily removed and replaced when necessary.

What we claim is:

1. In a window guide and sash construction, the combination of a guide in the form of a channel, the sash extending into the channel, the guide consisting of a body formed with one side and the bottom of the channel and a detachable member forming the other side of the channel, the detachable member being fulcrumed on the body between the inner and outer edges of said member forming a lever of the first class, and means

for moving it on its fulcrum against the sash the detachable member having a portion extending beyond the plane of the bottom of the channel and overlapping the adjacent side of the body, said means being located between the overlapping portion and the body, whereby said means is housed within the detachable member.

2. In a window guide and sash construction, the combination of a guide in the form of a channel, the sash extending into the channel, the guide consisting of a body formed with one side and the bottom of the channel and a detachable member forming the other side of the channel, the bottom of the channel being formed with openings, and the detachable member having projections extending into the openings and fulcrumed on the walls thereof, and means tending to move the detachable member about said fulcrum points and press the same against the sash.

3. In a window guide and sash construction, the combination of a guide in the form of a channel, the sash extending into the channel, the guide consisting of a body formed with one side and the bottom of the channel, said bottom being located intermediate of the inner and outer edges of the guide, and a detachable member forming the other side of the channel, the bottom of the channel being formed with openings and the detachable member having projections extending into the openings and fulcrumed on the walls thereof, the detachable member having a portion extending beyond the plane of the bottom of the channel and overlapping the adjacent side of the body, and spring means interposed between the overlapping portions of the body and the detachable member.

4. In a window guide and sash construction, the combination of a guide mountable in a window opening and being formed with a channel for receiving the sash, the bottom of the channel being located intermediate the inner and outer edges of the guide, the guide consisting of a body and a detachable member, the body being formed with one of the sides and the bottom of the channel and said bottom being formed with openings therethrough and the detachable member forming the other side of the channel and provided with prongs fulcruming on the walls of the openings and the detachable member having a flange lapping the contiguous side of the body below the bottom of the channel, and a spring interposed between the overlapping portions of the body and the detachable member.

5. In a window guide and sash construction, the combination of a guide mountable in a window opening and formed with a channel for receiving the sash, the guide comprising a hollow body formed with one of the sides and the bottom of the channel, the bottom

being located intermediate of the inner and outer edges of the body, the detachable member having a portion forming the other wall and channel and with a flange covering and spaced apart from the contiguous side of the body between the bottom of the channel and the wall of the window opening, the detachable member also having prongs located to extend through the openings in the bottom of the channel and fulcrum on the walls thereof, and a spring interposed between the said flange and the portion of the body spaced therefrom and tending to move the detachable member about said fulcrum to press the detachable member against the sash.

6. In a window guide and sash construction, the combination of a guide mountable in a window opening and formed with a channel for receiving the sash, the guide comprising a hollow body formed with one of the side walls and the bottom of the channel, the bottom being located intermediate of the inner and outer edges of the body and formed with an opening near the edge thereof remote from the side wall of the channel which is provided on the body, a detachable member having a portion forming the other wall of the channel and with an offset flange covering and spaced apart from the contiguous side of the body between the bottom of the channel and the wall of the window opening, the detachable member also having prongs extending from and in line with the portions engaging the sash and parallel to the offset flange, and located to extend through the openings in the bottom of the channel and fulcrum on the walls thereof, and a spring interposed between the spaced apart portions of the body and the detachable member and tending to move the detachable member about said fulcrum to press the detachable member against the sash, said prongs also interlocking in said openings upon an inward movement and lengthwise shifting of the detachable member.

7. In a window guide and sash construction, the combination of a guide in the form of a channel, the sash extending into the channel, the guide consisting of a body formed with one side and the bottom of the channel, and a detachable member forming the other side of the channel, the bottom being of greater width than the sash, whereby the margin thereof projects beyond the side of the sash adjacent said detachable member, the margin being formed with openings said detachable member having prongs extending into the openings and means for pressing the detachable member against the sash.

8. In a window guide and sash construction, the combination of a guide in the form of a channel, the sash extending into the channel, the guide consisting of a body formed with one side and the bottom of the channel, and a detachable member forming the other

side of the channel, the bottom being of greater width than the sash whereby the margin thereof projects beyond the side of the sash adjacent said detachable member, the margin being formed with openings, said detachable member having a portion overhanging said margin and formed with prongs for entering said openings.

9. In a window guide and sash construction, the combination of a guide in the form of a channel, the sash extending into the channel, the guide consisting of a body formed with one side and the bottom of the channel and a detachable member forming the other side of the channel, the bottom being of greater width than the sash whereby the margin thereof projects beyond the side of the sash adjacent said detachable member, said detachable member having a portion overhanging and resting on said margin.

10. In a window guide and sash construction, the combination of a guide in the form of a channel, the sash extending into the channel, the guide consisting of a body formed with one side and the bottom of the channel and a detachable member forming the other side of the channel, the bottom being of greater width than the sash whereby the margin thereof projects beyond the side of the sash adjacent said detachable member, said detachable member having a portion overhanging and resting on said margin, and means for pressing the detachable member against the sash.

11. In a window guide and sash construction, the combination of a guide in the form of a channel, the sash extending into the channel, the guide consisting of a body formed with one side and the bottom of the channel, said bottom being located intermediate of the inner and outer edges of the guide, and a detachable member forming the other side of the channel, the bottom of the channel being of greater width than the sash whereby the margin of the bottom projects beyond the side of the sash adjacent the detachable member, the detachable member having a portion extending outwardly beyond the plane of the bottom of the channel and overlapping the adjacent side of the body and a portion overhanging said margin and means for holding the detachable member in position on the body and against the sash.

12. In a window guide and sash construction, the combination of a guide in the form of a channel, the sash extending into the channel, the guide consisting of a body formed with one side and the bottom of the channel, said bottom being located intermediate of the inner and outer edges of the guide, and a detachable member forming the other side of the channel, the bottom of the channel being of greater width than the sash whereby the margin of the bottom projects

beyond the side of the sash adjacent the detachable member, the detachable member having a portion extending outwardly beyond the plane of the bottom of the channel and overlapping the adjacent side of the body and a portion overhanging said margin, 70 said margin being formed with openings and the detachable member with prongs for entering the openings.

13. In a window guide and sash construction, the combination of a guide in the form of a channel, the sash extending into the channel, the guide consisting of a body formed with one side and the bottom of the channel, said bottom being located intermediate of the inner and outer edges of the 75 guide, and a detachable member forming the other side of the channel, the bottom of the channel being of greater width than the sash whereby the margin of the bottom projects beyond the side of the sash adjacent the detachable member, the detachable member having a portion extending outwardly beyond the plane of the bottom of the channel and overlapping the adjacent side of the body 80 and a portion overhanging said margin, said margin being formed with openings and the detachable member with prongs for entering the openings, and means interposed between the lapping portions of the body and the detachable member for pressing the latter against the sash.

14. In a window guide and sash construction, the combination of a guide in the form of a channel, the sash extending into the channel, the guide consisting of a body formed with one side and the bottom of the channel, and a detachable member forming the other side of the channel, the bottom being of greater width than the sash whereby the margin thereof projects beyond the side of the sash adjacent said detachable member, said detachable member having a portion overhanging said margin, means for holding the detachable member in position on the body and against the sash and a sash holder on the sash and including a movable locking member located within the sash and projecting through the edge of the sash, the bottom of the channel having means for receiving the projecting end of the locking member.

15. In a window guide and sash construction, the combination of a guide in the form of a channel, the sash extending into the channel, the guide consisting of a body formed with one side and the bottom of the channel, said bottom being located intermediate of the inner and outer edges of the guide, and a detachable member forming the other side of the channel, the bottom of the channel being of greater width than the sash whereby the margin of the bottom projects beyond the side of the sash adjacent the detachable member, the detachable member 130

having a portion extending outwardly beyond the plane of the bottom of the channel and overlapping the adjacent side of the body and a portion overhanging said margin, 5 means for holding the detachable member in position on the body and against the sash, and a sash holder mounted on the sash and including a movable locking member located within the sash and projecting through the 10 edge thereof, the bottom of the channel having means for receiving the portion of the locking member which projects through the edge of the sash.

16. In a window guide and sash construction, the combination of a guide in the form of a channel, the sash extending into the channel, the guide consisting of a body formed with one side and the bottom of the channel, and a detachable member forming the other 20 side of the channel, the detachable member being interlocked by endwise movement of said member and means operable by such endwise movement for locking the detachable member from retrograde endwise movement 25 during raising and lowering of the sash due to its frictional engagement with the sash.

17. In a window guide and sash construction, the combination of a guide in the form of a channel, the sash extending into the 30 channel, the guide consisting of a body formed with one side and the bottom of the channel, and a detachable member forming the other side of the channel, the detachable member being interlocked by endwise movement of 35 said member and a spring secured to the body and acting on the detachable member to press it against the sash, the spring and said member having means for interlocking when said member is in its final position to prevent 40 retrograde endwise movement of said member during raising and lowering of the sash.

18. In a window guide and sash construction, the combination of a guide in the form of a channel, the sash extending into the 45 channel, the guide consisting of a body formed with one side and the bottom of the channel, and a detachable member forming the other side of the channel, the detachable member being interlocked by endwise movement of 50 said member and a spring secured to the body and acting on the detachable member to press it against the sash, the spring and said member having means for interlocking when said member is in its final position to prevent 55 retrograde endwise movement of said member during raising and lowering of the sash, the body and the spring having interlocking means coacting snap catch fashion to locate the spring relatively to the body whereby 60 the interlocking means of the spring and said member in turn are located to coact when the detachable member is in final position.

19. In a window guide and sash construction, the combination of a guide in the form 65 of a channel, the sash extending into the

channel, the guide consisting of a body formed with one side and the bottom of the channel, said bottom being located intermediate of the outer and inner edges of the guide, a detachable member forming the other 70 side of the channel, the bottom of the channel being of greater width than the sash whereby the bottom of the sash projects beyond the side of said sash adjacent the detachable member, the detachable member having a 75 flange portion extending outwardly beyond the plane of the bottom of the channel and overlapping the adjacent side of the body and a portion overhanging said margin of the bottom, said detachable member having 80 means for interlocking with the bottom by an endwise movement of the detachable member, a leaf spring interposed between the body and the flange portion of the detachable member and acting to press the detachable 85 member against the sash, said spring having a part embracing the body, said part and the body having interlocking means for locating the spring relatively to the body and the spring and flange portion of the detachable member having means for interlocking 90 when the detachable member is moving endwisely into its interlocking engagement with the bottom of the channel for preventing retrograde endwise movement of the detachable member during raising and lowering of the sash.

In testimony whereof, we have hereunto signed our names at Syracuse, in the State of New York, this 19th day of March, 1930 95 and at Elkhart in the State of Indiana, this 29th day of March, 1930.
